Application January 10, 1958, Serial No. 708,164

3 Claims. (Cl. 131—257)

This invention relates to cigarette holding clamps and may be considered an improvement on the subject matter of my Patent 2,582,097, granted Jan. 8, 1952.

An object of the invention is to simplify the patented device and render it more compact and thus reduce its cost of manufacture.

Another object is to provide a pivot to interconnect one clamping jaw with another and subject them to a single spring for maintaining either their open or closed position, such spring reacting between one of said jaws and a pin fixed on a support for the jaws.

Another object is to apply said spring to one of said jaws for movement with such jaw, by virtue of which movement said spring exerts pressure on such jaw in either open or closed position of the jaws.

Another object is to provide an aperture in one jaw to loosely engage said pin, and to predeterminedly space said pivot from a peripheral edge of said aperture to establish limits to opening and closing travel of said jaws.

These and various other objects are attained by the construction hereinafter described and illustrated in the accompanying drawing, wherein:

Fig. 1 is a front elevation of the device showing the jaws in their open position.

Fig. 2 is a similar view showing the jaws closed on a cigarette.

Fig. 3 is a partial view on a larger scale, showing details of the pin.

Fig. 4 is a view taken on the line 4—4 of Fig. 2.

Fig. 5 is taken in the same direction as Fig. 4, showing only one of the jaws.

Fig. 6 is taken in the same direction as Fig. 4, showing the other jaw with the spring secured thereto.

Fig. 7 is taken in the same direction as Fig. 4, showing the supporting member with the pin carried thereby.

In these views the reference character 1 designates a mounting bracket having mounting holes 2 for screws (not shown). An elongated arm 3 has an offset end portion 4 by which such arm is mounted on the bracket as with a pivot 5, thus spacing said arm 3 from the bracket in parallelism with the latter. Such arm is preferably formed of sheet material and integrally bears a jaw 6 bent transversely to the plane of the arm and arcuately formed to accommodate a cigarette.

A companion jaw 7 is similarly integrally formed upon a plate 8 and is appropriately contoured to coact with the jaw 6 to engage a cigarette. The plate 8 is disposed between the arm 3 and bracket 1 and is interconnected with said arm by a pivot 9. Such plate is formed with a tapered slot 10 to receive a pin 11 projecting from the bracket. Preferably, the pivot 9 is aligned with the longitudinal center line of said slot. A boss 12 on the plate 8 secures the end of an arm 13 of an approximately U-shaped spring disposed between the plate and the bracket. The other arm 14 of the spring is free, but bears under tension against the pin 11. This establishes a toggle relation between the jaws by virtue of which

2

they tend to open or close responsive to said spring according as the pivot 9 is shifted above or below "dead center" of the line established by the pivot 5 and the pin 11.

5 Said pin is formed with flat surfaces 11a, 11b, (Figs. 2, 3 and 7) transverse to the plane of the bracket and converging at an apex 11c on the aforesaid "dead center" line. In their normal position, the jaws are open, and the free arm 14 of the spring bears on the flat 11a. 10 When a cigarette A (in dash lines, Fig. 2) is introduced between the jaws and pressed lightly downwardly on the jaw 6, the pivot 9 travels arcuately about the pivot 5 toward the aforesaid "dead center" line. During such travel the arm 14 rides off the flat and on to the apex 11c, and, as said pivot 9 passes the "dead center" line said spring reacts to snap the jaws toward their closed position, while the arm 13 seeks to bear on the flat 11b. Absent a cigarette between the jaws, said arm 13 will bear substantially squarely upon the flat 11b. When the 15 jaws are gripping a cigarette, however (Fig. 2), they cannot move to the limit of their closed position, and the spring ram, unable to seat fully on the flat 11b is slightly compressed, as explained below, to exert tension on the upper jaw to prevent escape of the cigarette due to 20 vibration or light contact. Light upward pressure on the companion jaw 7 will move the pivot 9 upwardly past the "dead center" line, whereon the spring will be positioned to snap the jaws to their open position, with 25 spring arm 14 bearing on the flat 11a. 30 As, in its arcuate travel, the pivot 9 moves toward the "dead center" line, it approaches the pin 11, and conversely recedes from such pin as it moves away from said line. During such approach, the spring necessarily compresses, its stress increasing until the pivot 9 reaches dead center. The tapered slot 10 affords the requisite movement of the plate relative to the pin 11 and corresponding to that of the pivot 9. It is to be noted that the spacing of said pivot from the larger end of the 35 slot establishes limits to the arcuate travel of the pivot 9, and hence limits the open and closed positions of the jaws. 40

The device is useful under any conditions in which a smoker desires to be temporarily relieved of a cigarette, with assurance that it will be firmly held until he is ready 45 to use it. Such device may be advantageously installed in a motor vehicle or on an ash tray. Primary advantage of the device is its ease of manipulation, mere pressure of a cigarette serving to establish either limiting position of the jaws.

50 While the relationship of the pivots 5 and 9 and the pin 11 is essential, the base may vary widely from the form illustrated, and may if desired be a part of some other structure as for example, a vehicle dash.

55 What I claim is:

1. A gripping device comprising an elongated arm, a jaw formed on one end of such arm, a first pivot mounting the other end of the arm upon a supporting element, a companion jaw, a plate carrying said companion jaw, a pin projecting from said supporting element, said plate being adapted to so engage said pin as to afford movement of the plate relative to said pin, a second pivot interconnecting the plate and arm, and a spring having a pair of divergent arms, one such arm being secured to 60 the plate, and the other bearing movably against the pin, whereby said spring reacts between the pin and plate to exert pressure on the companion jaw in both open and closed positions of said jaws, there being a toggle relation between said arm and plate entailing travel of said 65 second pivot across the line established by the first pivot and the pin to open and close said jaws, said spring acting by virtue of such relation to resist both opening and 70

closing travel of the jaws, and said spring moving between respective positions predetermined relative to the respective open and closed positions of the jaws.

2. A gripping device as set forth in claim 1, the engagement of the plate and pin being effected by a hole formed in said plate to receive said pin and afford said movement of the plate relative to the pin, such hole being so located in the plate that a portion of the wall of the hole engages said pin in either position of said plate and disengages therefrom during said travel.

3. A gripping device comprising a support, an elongated arm, a jaw formed on one end of said arm, a first pivot mounting the other end of the arm on the support, a companion jaw, a plate carrying said companion jaw, a pin projecting from the support, said plate being formed with a hole receiving the pin, a second pivot interconnecting the plate and arm, a spring having a pair of

divergent arms, one such arm being fixed to said plate, the other arm bearing against the pin, said pin being formed with convergent flat surfaces engageable by said last mentioned arm, there being a toggle relation between 5 said arm and plate entailing travel of said second pivot across a line established by said pin and said first pivot, said spring acting by virtue of said relationship to alternatively bear on said respective flats to respectively resist opening and closing travel of said jaws, and said second pivot being predeterminedly spaced relative to said hole to establish limiting positions of said opening and closing travel.
